[57] CLAIM

The ornamental design for a speaker stand, as shown and described.

DESCRIPTION

FIG. 1 is a perspective view of the speaker stand showing my new design with the dashed lines illustrating a supported speaker unit;

FIG. 2 is a front elevational view thereof;

FIG. 3 is a side elevational view thereof;

FIG. 4 is a top plan view thereof; and

FIG. 5 is a bottom plan view thereof.

The speaker unit is shown in dashed lines in FIG. 1 for illustrative purposes only and does not form part of my claimed design.
